(57) **CLAIM**

The ornamental design for a sash lock and keeper, as shown and described.

DESCRIPTION

FIG. 1 is a left side elevational view of a sash lock and keeper showing our new design;
FIG. 2 is a right side elevational view thereof;
FIG. 3 is a rear elevational view thereof;
FIG. 4 is a front elevational view thereof;
FIG. 5 is a top front perspective view thereof;
FIG. 6 is a top rear perspective view thereof; and,
FIG. 7 is a top plan view thereof.
The broken lines environment is for illustrative purpose and forms no part of the claimed design.
